UNITED STATES PATENT OFFICE.

JULIUS H. HOLMGREEN, OF SAN ANTONIO, TEXAS.

REFRIGERATING APPARATUS.

No. 843,894.

Specification of Letters Patent.

Patented Feb. 12, 1907.

Application filed April 22, 1904. Serial No. 204,377.

To all whom it may concern:

Be it known that I, JULIUS H. HOLMGREEN, a citizen of the United States, and resident of San Antonio, in the county of Bexar and State of Texas, have invented certain new and useful Improvements in Refrigerating Apparatus, of which the following is a full, clear, and exact description, such as will enable those skilled in the art to which it appertains to make and use the same, reference being had to the accompanying drawings, forming a part of this specification.

The invention relates to improvements in refrigerating apparatus of that description in which the coil is composed of two pipes of different diameters placed one inside of the other and provided with means for causing the refrigerating medium to pass through one of the pipes to be acted upon by the cooling or condensing agent forced through the other pipe.

It more particularly relates to the construction of the coil in such devices. The coils of such device in ordinary use are generally flat and are formed of a series of straight pipes, placed one above the other and connected at their ends by joints or heads. In such constructions the relative movement of the inner and outer pipes, owing to the unequal expansion and contraction, causes their connections to work loose, with a consequential leakage. These connections also form pockets in which sediment or other obstructive matter collects and impairs the circulation. Also the use of these joints, which are numerous, and heads renders the construction cumbersome and expensive.

In the invention in the present instance it is proposed to form the coil of pipes helically arranged. By doing this a comparatively few joints will be required, and consequently fewer pockets will be formed to catch and retain the sediment or other obstructive matter to impair the circulation. and by using fewer joints the construction will be less cumbersome and less expensive. Also the strain occasioned by the unequal expansion and contraction of the pipes will be taken up by the resiliency imparted to the pipes by their helical formation and the creeping of the joints prevented and the consequential leakage avoided.

Coils composed of pipes placed one inside of the other and helically arranged have been used as heat-exchangers in sterilizing and other apparatus. In none of these instances,

however, are means provided for holding the two pipes concentric except at their extreme ends. Consequently for a considerable part of the length of the coil the inner pipe rests on the outer one. This contact of the two pipes prevents a proper circulation in the passage between them and acts as a trap to catch any sediment or obstructive matter carried by the medium or agent flowing through the passage. In time the accumulation of sediment in the lower part of the passage between the pipes would form an obstruction and would also diminish the radiating surface between the two pipes and the efficiency of the apparatus would be impaired. Also in these instances the coils are comparatively short, as no provision is made for connecting sections of pipe so that the helical formation can be given any considerable length.

In the present invention it is also proposed to provide means for holding the pipes comprising the helical coil in concentric relation throughout their entire lengths to form a continuous annular passage of uniform capacity. The holding means are utilized to control the flow of the medium or agent through the passage, so as to pursue a spiral course around the inner pipe, and thereby keep in motion any sediment or obstructive matter that might have a tendency to settle or collect in the outer pipe. This spiral flow of the medium or agent permits full advantage to be taken of the radiating-surface between the two pipes. Connections are provided that are particularly adapted to the purpose whereby the helical coil may be made of several sections of pipes, and thereby given any desired length.

The invention whereby the foregoing objects are accomplished consists in the novel construction, combination, and arrangement of parts, such as will be hereinafter fully described, pointed out in the appended claims, and illustrated in the accompanying drawings.

In the drawings, in which similar reference characters designate corresponding parts, Figure 1 is a side elevation of a coil embodying the invention. Fig. 2 is a plan view of the same. Fig. 3 is an enlarged detail view showing sections of the concentric pipes with the means for holding them in their proper relative positions. Fig. 4 is a cross-sectional view of the same. Figs. 5 and 6 are detail views of the holding or spacing plugs. Fig. 7 is an enlarged detail sectional view showing

the connection joining the ends of sections of the inner pipe. Fig. 8 is a similar view showing the by-pass connecting the ends of sections of the outer pipe.

5 The coil is composed of two concentric pipes 10 and 11, respectively, arranged so as to have a helical formation. It is held in shape and supported by the standards 12, made in sections bolted together at their 10 ends and clamped on opposite sides of the coil. The inner pipe 10 may be provided with any suitable means for forcing the refrigerating medium, such as ammonia-gas, through the same, and the outer pipe 11 may be connected with mechanism adapted to the purpose of circulating through the same the cooling or condensing agent, such as water. There is considerable annular space between the two pipes, and means are provided for 15 holding them in their proper concentric positions. The outer pipe is tapped at intervals and into the openings thus formed are turned the screw-threaded plugs 13 to impinge at their inner ends on the inner pipe at 20 right angles to the axis of both pipes. By adjusting these plugs the relative positions of the two pipes can be regulated so as to have a common longitudinal axis and so that the annular passage between them will be of 25 uniform cross-area throughout its entire length. These plugs are placed at regular intervals, so as to oppose each other, and are so disposed as to form a spiral line in the annular space between the pipes. Also they 30 are separated, so as to interfere as little as possible with the flow of the cooling or condensing agent. Each plug consists of the body portion 14, screw-threaded to engage with the opening in the pipe, the square head 35 15 to receive the turning-tool, and the flattened inner end 16. All the plugs are so placed that their flattened inner ends 16 stand at an angle relative to the longitudinal axis of the pipes, so as to form guides to cause 40 the cooling or condensing agent to take a spiral course through the annular passage. By taking such a course the agent will tend to keep in motion any sediment or obstructive matter that might have a tendency to 45 settle, and it will also insure an equal flow through all parts of the annular passage, so that full advantage can be taken of the radiating-surface between the two pipes. When it is desired to have access to the annular 50 passage for the purposes of inspection, the plugs can be readily removed. In the head of each plug is a slot 17 to show the position of the inner flattened end 16 and by means of which the proper adjustment of such end 55 60 in the annular passage will be facilitated.

When of considerable length, it will be necessary to construct the helical coil of sections of pipe joined together. For this purpose a coupling is provided for joining the ends of 65 the sections of the inner pipe and also a by-

pass to connect the ends of the sections of the outer pipe around the joint of the sections of the inner pipe. On the abutting ends of two sections of the inner pipe are the flanges 18, adjacent to which are the compressible gaskets 19, and over the latter and the flanges is the sleeve 20. Outside of the gaskets are the plates 21 with annular flanges 22 projecting between the sleeve and the pipe-sections and bearing against the gaskets. By means of the nuts 23 on the bolts 24, passing through the plates 21, the latter can be forced together to compress the gaskets and to secure the parts of the coupling together. In this way a gas-tight joint is 80 formed between two sections of the inner pipe.

The by-pass consists of two members 25, connected by a joint consisting of the sleeve 26, placed over the flanges 27 on the adjacent 85 ends of the members 25 and over the gaskets 28 outside of the flanges, and inserted in the ends of the sleeve are the flanges 29 on the plates 30, which are held in place by the bolts 31. The construction of this joint is substantially the same as the coupling connecting the ends of the sections of the inner pipe. On the inner pipe, adjacent to the ends of the outer pipe, are the casings 32, adjacent to the ends of the sections of the outer pipe. As 90 these casings are alike, a description of one will suffice for both. The casing has a rounded chamber 33, connecting with the annular passage formed by the inner and outer pipes, and from this chamber leads the member 25 100 of the by-pass, which is screwed into the casing. The latter has an internal flange 34, that abuts the end of the outer pipe, and an extension 35, that projects over the annular flange 36 on the end of the pipe and the gasket 37, adjacent to the flange. Projecting into the extension 35 and bearing on the gasket is the annular flange 38 of the collar 39. The latter is held in place by the screws 40, passing through the same into the casing. 105 By tightening the screws the flange 36 and the gasket 37 are clamped between the internal flange 34 of the casing and the annular flange 38 of the collar, and the casing is thereby held in place on the end of the outer pipe-section and leakage between the two is prevented. On the opposite side of the casing, which fits the inner pipe-section, is the annular extension 39', projecting over the inner pipe-section, and between the same and the pipe is the gasket 40', which is compressed by the flange 41 on the collar 42, inserted in the said extension. The collar is secured in place by the bolts 43, passing through the same into the body of the casing. 110 115 The by-pass thus formed is of sufficient carrying capacity to convey the medium or agent from one outer pipe-section to the other without interfering with the flow through the annular passage. By construct- 120 125 130

ing it in two parts it can be readily adjusted and fitted to the space between two outer pipe-sections.

While the herein-described construction is the preferred one, yet it can be departed from to a considerable extent without departing from the spirit of the invention. For an instance, different forms of couplings may be used for connecting the several parts.

10 Having thus described my invention, what I claim, and desire to secure by Letters Patent, is—

15 1. In refrigerating apparatus, a coil composed of helically-arranged pipes of comparatively long sections and free from joints and of different diameters placed one inside of the other, and plugs adjustably mounted in the outer pipe and impinging on the inner pipe to hold said pipes concentric to each

20 other thus forming an annular passage of uniform cross-area throughout and said plugs being spirally disposed to form a spiral course in the annular space between the pipes.

25 2. In refrigerating apparatus, a coil composed of helically-arranged pipes of comparatively long sections and free from joints and of different diameters placed one inside of the other thus forming an annular passage be-

30 tween the same, and guides mounted at intervals in said annular passage and spirally disposed therein to form a spiral course around the inner pipe.

35 3. In refrigerating apparatus, a coil composed of helically-arranged pipes of comparatively long sections and free from joints and of different diameters placed one inside of the other thus forming an annular passage between the same, and guides adjustably mounted at intervals in said annular passage and spirally disposed therein to form a spiral course around the inner pipe.

40 4. In refrigerating apparatus, a coil composed of pipes of different diameters placed one inside of the other and helically arranged, and plugs with flattened inner ends turned into the outer pipe and impinging on the inner pipe to hold said pipes concentric to

each other thus forming an annular passage between the same of a uniform cross-area throughout its length and with the flattened inner ends so disposed in said passage as to form a spiral course around the inner pipe.

5. In refrigerating apparatus, a coil composed of pipes of different diameters placed one inside of the other and helically arranged, and plugs with flattened inner ends and provided with indicating marks on their outer ends coincident with said flattened inner ends turned into the outer pipe and impinging on the inner pipe to hold said pipes concentric to each other thus forming an annular passage between the same of uniform cross-area throughout its length and with the flattened inner ends so disposed in said passage as to form a spiral course around the inner pipe.

6. In refrigerating apparatus, a coil composed of helically-arranged pipes of different diameters placed one inside of the other, and plugs with guides on their inner ends adjustably mounted in the outer pipe and impinging on the inner pipe to hold the said pipes concentric to each other thus forming an annular passage of uniform cross-area throughout and said plugs being spirally disposed and the guides adjusted to form a spiral course around the inner pipe.

7. In refrigerating apparatus, a coil composed of sections of pipes of different diameters placed one inside of the other and helically arranged, means for holding said pipe-sections concentric to each other to form an annular passage between the same, a joint connecting two inner pipe-sections, and a bypass consisting of two members joined at their inner ends and connected by couplings at their outer ends with the ends of two outer pipe-sections and extending around the joint connecting two inner pipe-sections.

In testimony whereof I hereunto affix my signature in the presence of two witnesses.

JULIUS H. HOLMGREEN.
